J. E. Merriman

Work Holder

No 10509

Patented Feb. 7. 1854

Fig. 2.

Fig. 1.

UNITED STATES PATENT OFFICE.

JULIUS E. MERRIMAN, OF MERIDEN, CONNECTICUT.

SEWING-BIRD.

Specification of Letters Patent No. 10,509, dated February 7, 1854.

To all whom it may concern:

Be it known that I, JULES E. MERRIMAN, of Meriden, in the county of New Haven and State of Connecticut, have invented a 5 new and useful Improvement in Sewing-Birds; and I do hereby declare that the following is a full, clear, and exact description of the same, reference being had to the accompanying drawings, forming 10 part of this specification, in which—

Figure 1, shows a side elevation of one of my sewing birds as it appears when resting on the edge of a table—excepting that the screw, which secures it to the table is 15 not shown screwed up its full length. In this view my improved method of arranging the cushion under the bird is shown, also the manner of combining the spring tape measure with the bird and cushion. Fig. 20 2, shows a side elevation of a modification of my invention, wherein the tape measure is dispensed with and the cushion under the bird employed.

The same letters of reference in each of 25 the two figures indicate corresponding parts.

The nature of my invention consists in employing in connection with the sewing bird, an ordinary spring tape line or measure, which is arranged in a hollow case of 30 cylindrical form directly under the belly of the bird, and may have placed on its top (the case) if desired a neat handsome pin or needle cushion. The said tape measure and cushion being placed in a position most 35 convenient for use and where they will add greatly to the beauty of the sewing bird. The tape measure thus arranged and employed in connection with a sewing bird is very useful and convenient and will save 40 considerable time and trouble—as the line is always at hand and can be used when wanted without leaving the seat, the sewing bird serving to hold the cloth and also the tape measure taut while either the sewing 45 or measuring operations are being performed, whereas if it were used independent of the bird it requires another person to hold the line while measuring.

To enable others to see more clearly the 50 construction of my sewing bird I will give a more definite description of the same.

A, represents a portion of a lady's work table.

B designates the screw clamp for securing 55 the sewing bird to the table A, in the manner shown in the drawing Fig. 1. This clamp has a vertical screw rest C, which extends some distance upward and has the

bird D, screwed on it as shown in Fig. 1. This rest has a shoulder a, at its lower end 60 on which the case F, which contains the spring tape measure E, rests or is sustained and prevented from turning. The tape line will be seen drawn a short distance out of the case in Fig. 1. This line 65 is arranged in the case on a hollow drum which is operated by a spiral spring arranged inside of it. This tape line is of great utility, when used in connection with a sewing bird, to milliners, dress makers and 70 others performing sewing operations, as it can be so easily and conveniently used.

G, is a neat handsome pin and needle cushion arranged on top the case F, and under the belly of the bird as seen in Fig. 1. 75 This position of the cushion is best suited to the position of the sewing lady and also adds greatly to the appearance of the sewing bird. Instead of placing the cushion on top of the case containing the tape meas- 80 ure I may see fit sometimes to employ a solid plate or flange b, Fig. 2 on the rest and place the cushion on it—in this case the tape line will be left off. I may also see fit to dispense with any cushion and 85 only employ the tape line. These alterations however will only take from the beauty and utility of the sewing bird and are only to be made for the sake of economy and cheapness. 90

The bird may be made of white ivory and be so constructed as to open its bills when pressure is exerted on its tail and to close the bills when the pressure is withdrawn, and bite on the work, by means of a spring 95 arranged on its inside and hid from view as shown in Fig. 1, by dotted lines.

What I claim as my invention and desire to secure by Letters Patent is—

Employing in connection with a sewing 100 bird, a spring tape measure, arranged in a case placed directly under the belly of the bird. The said case being so situated, that it may have if desired, a handsome pin or needle cushion placed on its top. This ar- 105 rangement rendering the sewing bird capable of measuring as well as holding the cloth while the sewing or measuring operations are being performed, and it also makes it more convenient for use, and ornamental 110 in its design as herein fully set forth.

JULIUS E. MERRIMAN.
